Primary Examiner — Vy N Koenig*Assistant Examiner* — Hillary Catherine Shepard(74) *Attorney, Agent, or Firm* — Stoel Rives LLP(57) **CLAIM**

I claim the ornamental design for an auditorium chair, as shown and described.

DESCRIPTION

FIG. 1 is an isometric view showing the front, right, top side of an auditorium chair according to my new design.

FIG. 2 is a bottom, rear, left isometric view of the auditorium chair.

FIG. 3 is front elevation view of the auditorium chair.

FIG. 4 is rear elevation view of the auditorium chair.

FIG. 5 is a left side elevation view of the auditorium chair.

FIG. 6 is a right side elevation view of the auditorium chair.

FIG. 7 is a top plan view of the auditorium chair; and,

FIG. 8 is a bottom plan view of the auditorium chair.

In FIGS. 1-8, the broken lines form no part of the claimed design.
